Primary Examiner — David Muller(74) *Attorney, Agent, or Firm* — Knobbe, Martens, Olson & Bear LLP(57) **CLAIM**

The ornamental design for a dental suction tool, as shown and described.

DESCRIPTION

FIG. 1 is a top perspective view of a dental suction tool configured in accordance with the present invention; FIG. 2 is a bottom perspective view thereof; FIG. 3 is a front elevation view thereof; FIG. 4 is a rear elevation view thereof; FIG. 5 is a left side elevation view thereof, the right side elevation view being a mirror image; FIG. 6 is a top plan view thereof, shown at a larger scale; and, FIG. 7 is a bottom plan view thereof, shown at a larger scale. The broken line showing of parts of the drawings is included for the purpose of illustrating use and environment and forms no part of the claimed design.
